UNITED STATES PATENT OFFICE.

WILLIAM WAGNER, OF WASHINGTON, DISTRICT OF COLUMBIA, ASSIGNOR
OF ONE-HALF TO OSCAR M. BALL, OF SAME PLACE.

TARGET-BALL.

SPECIFICATION forming part of Letters Patent No. 244,005, dated July 5, 1881.

Application filed May 23, 1881. (No model.)

To all whom it may concern:

Be it known that I, WILLIAM WAGNER, a resident of the city of Washington, District of Columbia, have invented certain new and useful Improvements in Target-Balls, of which the following is a specification, reference being had to the accompanying drawing, which illustrates a target-ball embodying my improvement.

As is well known, in practice marksmen use glass balls as targets. These balls, being thrown in the air by suitable means and being fragile, are shattered by the impact of the shot from the marksman's gun. It sometimes occurs that the distance from the marksman at which the ball is hit, or the slight number of shot striking the ball at such distance, renders it impossible to see and positively know that the ball has been hit at all, much less to know that it has been completely destroyed.

The object of my invention is to produce a target-ball which will readily and unmistakably disclose whether or not it has been struck either by a sufficient quantity of the charge to completely destroy it or by even a single shot of the charge, and this at any distance within range of vision. This object has been essayed by filling ordinary glass target-balls with feathers. I have found by experience that such filling, though having certain advantages over an unfilled ball, lacks certain other important advantages which attend the use of my improvement.

For a better understanding of my invention, I proceed to more particularly describe it.

A represents an ordinary glass ball (target) in section. The ordinary glass target-ball, having a neck suitable to receive and retain a cork or any suitable closing device, as paste or cement, may be used; or one having simply an opening, D, as shown, may be employed, in conjunction with a cover or patch, C, hermetically attached to and closing said opening of the ball; or said opening may be closed by fusing and uniting the glass of which the ball itself is made. Within the ball I place

dry powdered charcoal, which is admirably adapted to the ends in view. Into the ball A, I, through the opening D, place a sufficient quantity—a tea-spoonful, more or less—of such powder, (represented by B,) and then hermetically seal the opening by a cork, as heretofore mentioned, or by a patch, C. Said patch may be cloth, leather, paper, or any other well-known fabric, and it may preferably be secured, by any suitable cement, paste, or gum, to the outer or inner surface of the ball and over the opening D.

I do not limit myself to the quantity of powdered substance put into each ball, only preferring in practice to have a body of confined air within the hermetically-sealed ball with the powder, though it may be completely filled with said powdered substance.

The operation of my improved ball in use is as follows: It is projected into the air by the usual means, and upon being fractured the powder falls in the form of a cloud, and when only punctured by a single shot the powder is, by the displacement of air by the entrance of the shot into the ball, forced or puffed out through the puncture, and in a cloud or dust like form, thus unmistakably disclosing the fact that the ball has been hit.

I am aware that a ball has been known containing flour for the same purpose; but I consider flour objectionable, because it makes a white cloud and is adhesive when moist. After many experiments I have found that charcoal is free from these objections and best adapted for this purpose, and to such I confine myself.

Having described my invention, what I claim, and desire to secure by Letters Patent, is—

A glass target-ball containing a quantity of powdered charcoal and having a single opening, which is hermetically sealed after the ball is charged, substantially as set forth.

WILLIAM WAGNER.
